UNITED STATES PATENT OFFICE.

ALBERT SECHRIST, OF DENVER, COLORADO, ASSIGNOR TO THE ALBERT SECHRIST MANUFACTURING COMPANY, OF DENVER, COLORADO, A CORPORATION OF COLORADO.

CHANDELIER.

1,045,084.

Specification of Letters Patent.

Patented Nov. 19, 1912.

Application filed August 5, 1912. Serial No. 713,278.

To all whom it may concern:

Be it known that I, ALBERT SECHRIST, a citizen of the United States, residing in the city and county of Denver and State of Colorado, have invented certain new and useful Improvements in Chandeliers; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in chandeliers of the general character set forth in previous patents issued to me, and numbered 1,017,694, dated February 20, 1912; 1,024,369, dated April 23, 1912, and 1,024,809, 20 dated April 30, 1912.

My present invention relates to certain improvements over the constructions disclosed in the aforesaid patents, whereby the various parts of the chandelier structure are 25 more securely connected, and danger of damaging insulation of wires located in the chandelier is made practically negligible.

Having outlined in a general way my present improvement, I will proceed to describe the same in detail, reference being made to the accompanying drawing, in which is illustrated an embodiment thereof.

In this drawing: Figure 1 is a section taken through a chandelier embodying my 35 improved features. Fig. 2 is a fragmentary detail view illustrating the manner of connecting one of the end fittings, shown on a larger scale. Fig. 3 is a sectional view on the line 3—3 of the same. Fig. 4 is a detail 40 view of a screw-pin, constituting an important feature of my improvement. Fig. 5 is a view similar to Fig. 2, but showing a slightly modified form of construction. Fig. 6 is a fragmentary view of the inner extremity of one of the tube arms, shown on 45 a larger scale than in Fig. 1.

The same reference characters indicate the same parts in all the views.

Let the numeral 5 designate a fixture 50 body in which is located a tube connector 6, which is supported in the said body and connected with tube arms 7 which enter the fixture body through openings 8 in opposite sides thereof, the inner extremities of

the tube arms being fitted over nipples 9, 55 screw-pins 10 being employed to connect the tube arms with the nipples of the tube connector. This screw-pin has an enlarged threaded part 12 adjacent its head extremity, while the remaining portion 13 of the pin 60 is of less diameter and unthreaded. In applying these pins the enlarged threaded parts 12 engage slots 4 formed in the tube arms and threaded openings formed in the nipples 9 on one side. The extremities of 65 the plain portions of the screw-pins enter registering openings formed in the tubes and nipples on the opposite side from the said slots and threaded openings, the said 70 registering openings being plain or unthreaded. In making this connection, it is only necessary to apply the screw-pins to the nipples 9, care being taken not to insert the said pins far enough to cause their plain or unthreaded extremities to extend beyond 75 the nipple. Under these circumstances the heads of the screw-pins will extend above the nipples to permit the connection of the tube arms with the nipples, the tubes being so arranged that the mouths of the slots 4 80 are in alinement with the threaded portions of the screw-pins. The tubes are then moved toward the shoulders of the tube connector whereby the threaded portions of the screw-pins are caused to engage the slots 4. 85

As soon as the adjacent extremities of the tube arms are in engagement with the shoulders of the tube connector, the tube arms are given a partial rotation to cause the screw-pins to enter the off-set portions of 90 the slots 4, thereby forming bayonet joint connections. The screw-pins are then inserted to their limit of movement whereby their heads are caused to engage the tube arms, while their opposite extremities are 95 passed through the registering openings formed in the nipples and tube arms on the opposite side from the slots and threaded openings in the same parts. Where the angular slot 4 is employed, it will be seen 100 that the tube arms are doubly locked to the tube connector, since the tube arms cannot be removed without first unscrewing the screw-pins far enough to disengage their plain extremities from the openings in the 105 tube arms, and then giving the tube arms a partial rotation to bring the screw-pins into alinement with the portions of the slots 4.

extending parallel with the axes of the tubes. For this reason it will be understood that the angular slots may be dispensed with and straight slots employed if desired. 5 By virtue of this peculiar construction of the screw-pins and the arrangement of the perforations which the said pins engage, the assembled parts may be quickly connected and disconnected, as compared with cases where screws whose shanks are threaded their entire length, are employed.

To the tube connector 6 is further applied a lower spacing sleeve 1 and an upper spacing sleeve 2. The inner extremities of 15 these sleeves engage the connector 6. A rod 3 is passed through the central opening 14 formed in the tube connector and through the upper and lower sleeves of the structure. The upper extremity of this rod 20 is threaded into a joint 15, a lock-nut 16 being applied to the upper extremity of the rod and interposed between the upper extremity of the spacing sleeve 2 and the lower end of the joint 15. The lower end 25 of the spacing sleeve 1 engages the bottom of the fixture body 5 surrounding the opening in the bottom of the said body, through which the rod 3 extends. Applied to the lower threaded extremity of this rod, and 30 fitted against the bottom of the canopy on the outside, is a nut 17 which is countersunk in a recess 18 formed in the bottom knob 19 whose perforation 20 is threaded to receive the rod. The upper extremity of 35 this bottom knob is fitted closely against the bottom of the canopy on the outside.

To the outer extremities of the tube arms are applied end fittings 21 upon which are formed nipples 22 which are inserted in the 40 outer extremities of the tube arms and secured thereto by screw-pins 10 of the construction heretofore described. These screw-pins, by virtue of the fact that they pass entirely through the nipples and the 45 tubular parts with which the nipples are connected, make it impossible for the connected parts to become loose, consequently there is no tendency for one part to move or rock upon the other in such a manner 50 that the insulation on the electrical conductors which must pass through the connected parts, might become worn or destroyed.

The screw-pins 10 which connect the end 55 fittings with the tube arms may be employed in connection with slots 24 of angular shape, whereby a bayonet joint is formed,—see Fig. 2,—or with straight slots 25,—see Fig. 5.

60 The lower extremity of a tube stem 26 is connected with a nipple 27 formed on the upper extremity of the joint 15, by means of a screw-pin 10, the said nipple of the joint being inserted in the lower end of the said 65 stem. This connection is made in the same

manner as the other screw-pin connections heretofore described. The upper portion of this stem extends into a ceiling canopy 29 which is supported on the tube stem by a set-screw 29 passed through an opening 70 formed in a bead 30 formed on the lower extremity of the ceiling canopy and surrounding the tube stem. The inner extremity of the set-screw engages the tube-stem with sufficient force to maintain the ceiling 75 canopy in its proper position of vertical adjustment.

Within the ceiling canopy, and connected with the upper extremity of the tube stem, is a fixture stud 31 which is connected with the top of the tube stem by means of a bolt 32, a nut 33 being applied, the connection being made in such a manner that the joint is sufficiently loose to permit the chandelier to hang in a vertical position. The upper 80 extremity of the fixture stud is threaded into the lower end of a joint 34, whose upper extremity is connected, as shown at 35, with an insulating joint 36, this insulating joint being connected with a member 37 located 90 in a ceiling cavity 38 in which is set an inverted cup-shaped member 39 which is surrounded, and normally entirely concealed, by the ceiling canopy.

From the foregoing description, my improved construction, as well as the manner of assembling the various parts thereof, will be readily understood. For instance, in applying the end fittings to the tube arms, the screw-pins are first placed in the position 100 shown in Fig. 3, whereby their plain or unthreaded extremities do not extend beyond the nipples, the heads of the screw-pins being raised considerably from the nipples. The nipples are then inserted in the outer 105 extremities of the tube arms, causing the threaded portions of the screw-pins to enter the slots 24 or 25, as the case may be. As soon as the nipples are inserted to their limit of movement, if the angular form of 110 slot is employed, the end fittings will be given a partial turn to cause the screw-pins to enter the offset portions of the slots, after which the screw-pins will be inserted to their limit of movement thus securely locking the end fittings in place. The other screw-pin connections will be made in substantially the same manner, and need not be described in detail. By virtue of my improved screw stem connections heretofore 120 described, the said parts are much more quickly and easily joined than by any of the devices heretofore employed; for instance, referring to the manner of connecting the tube arms 7 with the tube connector 125 6, it is only necessary to apply the tubes to the nipples with the screw-pins properly adjusted. The operator then can pass a screw-driver downwardly from the top of the fixture body and readily screw the pin to po- 130

sition. Heretofore, in cases where the fastening devices pass entirely through the connected parts, and nuts are employed to secure the fastening devices in place, great difficulty is experienced in assembling the parts, as will be readily understood. Furthermore, by virtue of my improved construction, it becomes practicable to shift the tube connectors, the end fittings and the joints employed in connection with the lower extremities of the screw stems, with the screw pins in place, thus greatly facilitating the work of assembling the parts.

Attention is called to the fact that my improved screw-pin connections are equally applicable to parts which are square, or of other polygonal shape in cross section. However, when the parts to be connected are of polygonal shape it will be understood that the straight form of slot 25 will be employed, since the angular form of slot is only practicable where one part can be rotated upon the other, at least to a limited extent.

Attention is also called to the fact that the tube connector 6, the tube arms 7, the upper and lower spacing sleeves and the rod 3 passing through the said connector and the said sleeves constitute a rigidly assembled structure independently of the fixture body, the screw-pins being employed to connect the tube arms with the tube connector and the nuts 16 and 17 applied to the opposite extremities of the rod for securing the spacing sleeves in position. It, therefore, results that if the fixture body were injured or destroyed, the rigidity and security of the structure would not be interfered with.

It should be stated, further, that the important object of having the portions of the screw-pins plain or unthreaded where they pass through the openings in the nipples, is that there is no danger of injuring the insulation of the electrical conductors which must pass through these openings. In cases where the connecting screws are threaded throughout their length, the sharp edges of the screw threads are liable to destroy the insulation on the conductors; as the latter are drawn there-through, or during use.

Having thus described my invention, what I claim is:

1. A chandelier comprising a fixture body having openings on opposite sides, tube arms entering said openings, a tube con-

nector within the fixture body, the said connector having nipples which enter the extremities of the tube arms, and screw-pins for attaching the tube arms to the said connector, the said pins having threaded portions adjacent their heads, the connected parts being perforated to receive the screw-pins which pass entirely through the same, one set of the perforations in the nipples being threaded to receive the threaded portions of the screw-pin, substantially as described.

2. A chandelier comprising a fixture body, a tube arm connector inclosed within the fixture body, said connector being vertically perforated, a rod passing through said perforation, upper and lower spacing sleeves engaging the tube arm connector at opposite ends, the lower spacing sleeve being interposed between the said connector and the bottom of the fixture body, the lower extremity of the rod passing through an opening formed in the bottom of the fixture body and being threaded, a bottom knob applied to the said threaded end, and a nut also applied to said threaded end and countersunk in a recess formed in the top of the knob.

3. The combination of a tube, a part equipped with a tubular nipple, and a screw-pin having a threaded part adjacent its head, and a plain or unthreaded part beyond, the tube and nipple having a slot and threaded opening respectively on one side adapted to receive the threaded part of the screw-pin, and registering perforations on the opposite side to receive the plain or unthreaded portion of the screw-pin.

4. A chandelier including a tube connector, radially disposed tube arms applied to the tube connector and rigidly secured thereto, upper and lower spacing sleeves whose inner extremities engage the tube connector, a rod passed through the spacing sleeves and an opening formed in the connector, the rod having threaded extremities extending beyond the sleeves, and nuts applied to the opposite extremities of the rod.

In testimony whereof I affix my signature in presence of two witnesses.

ALBERT SECHRIST.
